FORM CLAMP

Harold K. Nansel, Waverly, Nebr., assignor to Burg Manufacturing Company, Waverly, Nebr., a corporation of Nebraska

Filed Feb. 19, 1963, Ser. No. 259,758

12 Claims. (Cl. 269—236)

Form clamps of various descriptions have been extensively used in the construction business in the fabrication of concrete wall forms. Among the functions of these clamps are to anchor the wall ties and to hold the forms together. Many existing clamps require the assembly and disassembly of the parts thereof as the clamp is being used in various phases of its operational cycle. Other clamps serve to interfere with the vertical form reinforcing members, and some cannot be operated without special tools.

Therefore, a principal object of my invention is to provide a form clamp that can be actuated through all phases of its operational cycle without being disassembled or reassembled.

A further object of my invention is to provide a form clamp which will effectively hold the horizontal reinforcing members against the form, and which will stabilize the wall ties.

A still further object of my invention is to provide a form clamp that will facilitate the use of vertical form reinforcing members in addition to accommodating the horizontal reinforcing members.

A still further object of my invention is to provide a form clamp that can be easily operated.

A still further object of my invention is to provide a form clamp that will tend to lock itself to the horizontal reinforcing member by forcibly penetrating the horizontal member.

A still further object of my invention is to provide a form clamp that will not easily become inoperative because of excessive forces being exerted on its component parts.

A still further object of my invention is to provide a form clamp that will accommodate horizontal reinforcing members of different dimensions.

A still further object of my invention is to provide a form clamp that will hold itself in a locked operative position at times.

Still further objects of my invention are to provide a form clamp that is economical in manufacture, durable in use, and refined in appearance.

These and other objects will be apparent to those skilled in the art.

My invention consists in the construction, arrangements, and combination, of the various parts of the device, whereby the objects contemplated are attained as herein-after more fully set forth, specifically pointed out in my claims, and illustrated in the accompanying drawing, in which:

FIGURE 1 is a top plan view of my device in its released position;

FIGURE 2 is a side elevational view of my device in its released position;

FIGURE 3 is a side elevational view of my device in its operative position;

FIGURE 4 is a sectional view of my device taken on line 4—4 of FIGURE 2;

FIGURE 5 is a partial plan view of my device as it is operatively mounted on a wall construction form as viewed on line 5—5 of FIGURE 6, and

FIGURE 6 is a side elevational view of my device in its operative position and mounted on a wall form.

I have used the numeral 10 to designate the vertical sheet of a wall form which is normally comprised of two

2

opposing spaced apart sheets 10 which are interconnected by a plurality of wall ties 12. Wall ties 12 consist of an elongated wire or rod which has its opposite ends terminating in hooks 14. A flattened portion or stop element 16 is formed near each end of tie 12 inwardly from hook 14. Hooks 14 extend outwardly through vertical slots 18 in sheets 10. A frusto-conically shaped spacer element 20 has its inward flange 22 bearing against stop element 16 and the outward flange 24 bears against the inner surface of sheet 10. The diameter of spacer element 20 becomes progressively greater from its inward to its outward end. A bore on its longitudinal axis allows it to loosely embrace the tie 12. Only one end of these ties has been shown in FIGURES 5 and 6.

5 An inverted U-shaped bracket 26 is comprised of sides 28 and top 30. A reinforcing angle 32 is secured to and extends between the lower forward ends of the bracket. A pair of parallel slots 34 extend longitudinally along the side edges of the top 30 of bracket 26. A tapered arcuate slot 36 extends rearwardly and thence forwardly from the forward center edge of the top of the bracket. Slot 36 is adapted to receive and hold the hook 14 on wall tie 12 at times.

An inverted U-shaped carriage 38 is comprised of top 40 and sides 42. A pair of rectangularly-shaped arms 44 extend downwardly and forwardly from the forward ends of sides 42 of carriage 38. Arms 44 extend down through the slots 34 in bracket 26 so that the upper edges of the forwardly extending arms slidably bear against the lower surface of the top of bracket 26. The lower edges of arms 44 slidably engage the top of the angle 32 which extends across the lower forward end of bracket 26. At the same time, the lower edges of the sides 42 of carriage 38 slidably bear against the upper surface of the top 30 of the bracket. The rearward end of carriage 38 is bent upwardly to form a vertically disposed U-shaped bracket 46. A horizontally disposed forwardly extending V-shaped element 48 is stamped into the upper end of bracket 46. A spring 50 has one of its ends secured to 20 the forward top end of carriage 38 and its other end secured to the rearward top end of bracket 26 to normally hold the carriage in a rearward position.

A pin 52, which is circular in cross section, is horizontally disposed and is secured by its ends in the sides 28 45 of bracket 26. As shown in FIGURES 2 and 3, pin 52 is located centrally of bracket 26 at a position vertically below the rearward ends of slots 34 in the top of the bracket. A U-shaped yoke 54 is comprised of a normally horizontal bottom portion 56 with two upstanding side portions 58. Pin 52 extends through aligned apertures in the side portions of the yoke at the upper ends thereof to rotatably support the yoke on the pin within the bracket 26. It will be noted that the side portions 58 of yoke 54 are in spaced relationship to the sides 28 of bracket 26. A 55 roll pin 60 similar to pin 52 is rotatably mounted in the side portions 58 of yoke 54 in parallel and spaced relationship to pin 52. As shown in FIGURE 2, roll pin 60 is normally directly below pin 52, and both pins are in engagement with the rearward vertical edges of arms 44 when my device is in its inoperative position. A retainer pin 62, which is circular in cross section, is positioned on yoke 54 in-between pins 52 and 60 and is in direct engagement with the entire lengths of both pins 52 and 60. Retainer pin 62 is rigidly secured to yoke 54 and its ends movably touch the inner surface of the sides 28 of bracket 26 to stabilize the yoke in a lateral direction. In addition, pins 52 and 62 serve to uniformly support the roll pin 60 so that the forces exerted on the roll pin by the arms 44 will not deflect or damage the roll pin. A straight handle 64 is secured in any convenient manner to the bottom portion 56 of yoke 54, and the handle normally extends rearwardly from the yoke.

It will be noted that the rearward ends of the sides 28 of bracket 26 extend beyond the rearward end of the top 30. This leaves open the area vertically below and behind bracket 46 on carriage 38. This notch opening in the rearward end of the top of bracket 30 permits a 2" x 4" vertical member to be received within the bracket 46. Both the sides of bracket 46 and the rearward side portions of bracket 26 would serve to engage and laterally support such a vertical member.

The normal operation of my device is as follows: When the sheets 10 and ties 12 have been assembled according to FIGURES 5 and 6, the hook 14 is received into and fixedly engaged within the arcuate slot 36 on the forward end of bracket 26. A horizontal member, such as 2" x 4" member 66 is positioned as shown in FIGURE 6. At that time, the various components of my device are in the positions shown in FIGURES 1 and 2. At that point, the handle 64 is pivoted downwardly to the general positions shown in FIGURES 3 and 6. This causes yoke 54 to rotate on pin 52, and causes roll pin 60 to rotatably push forward on the rearward vertical edges of arms 44 of carriage 38. This force overcomes the tension in spring 50 and the carriage starts to slide forward on bracket 26. This, in turn, causes the vertical bracket 46 on the rearward end of the carriage 38 to move forwardly against the horizontal member 66 to bind this member against the sheet 10. The bracket 26 is stabilized by its then rigid engagement with hook 14 on the end of tie 12, for tie 12 is held immobile with respect to sheet 10 by element 20. Great stresses are imposed on both pin 52 and pin 60, but pin 62 tends to equally distribute these stresses throughout the lengths of pins 52 and 60. The V-shaped element 48 on bracket 46 will make an indentation in the cross member 66 to more rigidly anchor the cross member.

It will be noted that when handle 64 is moved downwardly, a vertically disposed 2" x 4" member or the like is adapted for insertion in the notch compartment formed by the rear portions of brackets 46 and 26. Also, by viewing FIGURE 3, it is seen that pin 60 is moved slightly more than 90 degrees from the inoperative position of FIGURE 2, whereupon the spring 50 tends to urge the carriage rearwardly. This tends to continue the tendency of pin 60 to move in a clockwise direction, as viewed in this figure, which holds yoke 54 and handle 64 from returning to its original position.

After my unit has been so installed and the concrete has been poured and hardened, a removal of the above-mentioned vertical member will permit handle 64 to be raised, whereupon, spring 50 will withdraw carriage 38 rearwardly, and the binding action on horizontal member 66 and tie 12 will be released. Hook 14 is then disengaged from arcuate slot 36 in bracket 26, and my device is then free for repeated use. The ends of ties 12 are subsequently broken off and the void space left by elements 20 is filled with grout after the form has been completely stripped.

Thus, from the foregoing, it is seen that my device will accomplish at least all of its stated objectives.

I claim:

1. In a form clamp, a bracket, a carriage movably secured to said bracket, a bracket element on said carriage for engaging a form supporting member, means on said bracket for receiving and retaining the hook on a concrete wall tie, connecting means connecting said carriage and said bracket, and lever means secured to said connecting means whereby said connecting means can be moved against said carriage to move said bracket element against a supporting member on said carriage.

2. The structure of claim 1 wherein a yieldable means extends between said bracket and said carriage to yieldably resist the relative movement therebetween by said lever means.

3. In a form clamp, an inverted U-shaped bracket having a top, two sides, and rearward and forward ends, a pair of elongated slots in said bracket, a carriage on the

top of said bracket, arms on the forward end of said carriage and extending forwardly and downwardly therefrom through said slots, a cam means mounted within said bracket and being in engagement with said arms whereby the rotation of said cam means in one direction will move said carriage forwardly on said bracket, and means on said bracket for receiving and retaining the hook on a concrete wall tie.

4. The structure of claim 3 wherein a spring connects said bracket and said carriage to yieldably resist the movement of said carriage by said cam means.

5. The structure of claim 3 wherein said carriage is shaped to receive a horizontal form brace which is rectangular in cross section, and the rearward ends of said carriage and said bracket are shaped to receive a vertical form brace of similar dimensions to said horizontal form brace.

6. The structure of claim 3 wherein said cam means includes a yoke, a horizontal pin pivotally securing said yoke to said bracket, and a roll pin rotatably mounted on said yoke and engaging said arms whereby rotation of said yoke in one direction will move said carriage forwardly on said bracket.

7. The structure of claim 3 wherein said cam means includes a yoke, a horizontal pin pivotally securing said yoke to said bracket, a roll pin rotatably mounted on said yoke and engaging said arms whereby rotation of said yoke in one direction will move said carriage forwardly on said bracket and a retaining pin in between said pin and said roll pin and being in longitudinal engagement with both of said pins.

8. The structure of claim 3 wherein a spring connects said bracket and said carriage to yieldably resist the movement of said carriage by said cam means, said cam means including a yoke, a horizontal pin pivotally securing said yoke to said bracket, and a roll pin rotatably mounted on said yoke and engaging said arms whereby rotation of said yoke in one direction will move said carriage forwardly on said bracket, said roll pin normally being positioned below said pin when said carriage is in its rearmost position with respect to said bracket, and being normally in a position above said pin when said carriage is moved to its forwardmost position.

9. The structure of claim 3 wherein said arms are substantially rectangular in shape and include a rearward vertical edge, and said cam means engages and is adapted to move against the vertical rearward edges of said arms.

10. The structure of claim 3 wherein said cam means includes a lever extending substantially vertically downwardly when said carriage is positioned above said bracket in its forwardmost position.

11. In a form clamp, a bracket, a carriage movably secured to said bracket, a bracket element on said carriage for engaging a form supporting member, means on said bracket for receiving and retaining the hook on a concrete wall tie, connecting means connecting said carriage and said bracket, and lever means secured to said connecting means whereby said connecting means can be moved against said carriage to move said bracket element against a supporting member on said carriage, said connecting means including a yoke means, a pin rotatably extending through said bracket and supporting said yoke, and a roll pin rotatably extending through said yoke and being in engagement with said carriage.

12. In a form clamp, a bracket, a carriage movably secured to said bracket, a bracket element on said carriage for engaging a form supporting member, means on said bracket for receiving and retaining the hook on a concrete wall tie, connecting means connecting said carriage and said bracket, lever means secured to said connecting means whereby said connecting means can be moved against said carriage to move said bracket element against a supporting member on said carriage, said connecting means including a yoke means, a pin rotatably extending through said bracket and supporting said yoke,

and a roll pin rotatably extending through said yoke and being in engagement with said carriage, and a retaining pin disposed between said pin and said roll pin and being in engagement therewith.
